UNITED STATES PATENT OFFICE.

FRANK A. YOUNG, OF NEW YORK, N. Y., ASSIGNOR TO UNDERWOOD TYPEWRITER COMPANY OF NEW YORK, N. Y., A CORPORATION OF NEW JERSEY.

TYPE-WRITING MACHINE.

No. 925,411.

Specification of Letters Patent. Patented June 15, 1909.

Application filed March 17, 1909. Serial No. 483,928.

To all whom it may concern:

Be it known that I, FRANK A. YOUNG, a citizen of the United States, residing in New York, in the county of New York and State of New York, have invented certain new and useful Improvements in Type-Writing Machines, of which the following is a specification.

This invention relates generally to tabulating mechanism for typewriting and other machines, and particularly to means for enabling the carriage to jump to any selected column or field, such devices known in the art as "column skippers".

The principal object of the invention is to produce a simple and inexpensive mechanism readily applicable to typewriting machines for effecting such jumping of the carriage.

In carrying out my invention in one form the column stops are placed at any desired intervals along a rack provided upon the carriage, and a single stop is mounted upon the main frame of the machine to coöperate with said column stops as desired, for arresting the carriage. At the keyboard of the machine is mounted a row of column stop keys numbered to correspond with the column stops. Said keys are connected to means for causing said single stop upon the main frame to rise at the proper time to engage that stop which corresponds to the actuated key. If, after returning the carriage to begin a new line, the operator desires to write in the first column, he depresses the key marked "1", and said main-frame stop is caused to engage the first column stop in the series to arrest the carriage at that point. If then the operator wants to write in the fifth column for instance, he depresses the key marked "5", and said main-frame stop is caused to rise to engage the fifth column stop and arrest the carriage at that point; and so on.

To accomplish the aforesaid results each column stop is provided with a tappet, and upon the frame of the machine is mounted an interponent to be engaged and operated by the tappets, and in turn to thrust up the single stop which is mounted on the main frame; or in other words, the movement of the carriage is made available to cause the main-frame stop to project into the path of one of the column stops on the carriage. Said tappets are of graduated lengths, or at least are arranged in echelon, and said interponent is thrust up variably by the different keys; the

interponent being operated by a stepped member and the keys having levers which engage the different steps; the first key thrusting the interponent up to its highest in position, to be engaged and operated by the shortest tappet; the second key engaging the next step on the interponent - carrier, to thrust the interponent up not quite so high, in position to skip the first tappet and to be engaged by the second; and so on for the whole series.

It will be seen that certain features of the invention may be used for other purposes than column-skipping.

In the accompanying drawings, Figure 1 is a perspective rear view of the present improvements applied to an Underwood front strike typewriting machine. Fig. 2 is a sectional side elevation of the same; one of the column-selecting keys being shown depressed. Fig. 3 is a perspective front view of the column-selecting devices illustrating the manner in which the carriage is caused to thrust up the main-frame stop to arrest the carriage. Fig. 4 is a perspective view to illustrate the manner of connecting a key-stem to a key-lever. Fig. 5 is a perspective view of a numbered column stop (with its integral tappet) and the stop on the main frame. Fig. 6 illustrates the series of column stops in front edge view separated from the column-stop rack; this view illustrating the echelon arrangement of the tappets on the column stops.

In said machine types 1 are caused by keys 2 to strike against the front side of a platen 3, which is mounted upon a carriage 4, sliding on one or more rails 5 and connected by a strap 6 to a spring-barrel 7. Upon the carriage is provided a releasable rack 8, which meshes with a pinion 9 forming part of an escapement mechanism.

Keys 10 are arranged in a row at the back of the keyboard of the machine and are numbered from 1 to 10, to correspond with the numbering of a set of column stops 11 adjustable along a rack 12 provided upon the carriage 4; each column stop formed of a plate of sheet metal and comprising forks 13, 14, and having at its rear end an extension 15 turned over to form a number-bearing ear 16. It will be understood that there are as many column stops as keys, and that the first column stop is numbered 1, and is at the left hand end of the rack in Fig. 3, to be the

first one available at the beginning of a new line of writing, and intended to be brought into play by a depression of the first key in the row, which key bears the number "1".

Upon the lower fork 14 of each of the column-stops is formed a tappet 17; that on the first column stop being the highest and that on the last column stop being the lowest, and the others in regularly graduated intervening positions, Figs. 3 and 6. These tappets are in the nature of extensions, to stand in front of the column-stop rack 12, but without interfering with the convenient withdrawal and insertion of the stops on the rack; a locking-bar 18 being provided to engage shoulders 19 to lock the column stops upon the rack, said locking-bar hinged at its ends at 20 to swing upwardly and rearwardly from the column stops to release them for withdrawal and free adjustment. A single stop 21, below the column stops 11, (the latter projecting downwardly from the bottom of the rack) is mounted in lower and upper guides 22 and 23, to slide upwardly into the path of any of the column stops.

The movement of the paper carriage 4 is caused to project the stop 21 up into the path of any desired column stop. This action occurs at such a point in the travel of the carriage that the stop 21 does not rise until it is immediately approached by the selected column stop, so that there is no liability of engagement thereof with the wrong column stop. This movement of the stop 21 is secured by the co-operation of an interponent device or mechanism, which is brought into position to be actuated by the selected tappet, and when so actuated operates to lift the stop 21 immediately in advance of the column stop to which the selected or acting tappet belongs. The interponent mechanism comprises a finger or device 24 pivoted at 25 to vibrate along the rack; and a lever comprising two arms 26, 27 fulcrumed at 28 upon a fixed part 29 of the framework. When the device 24 is engaged by a tappet 17, it is swung to the upright position, Fig. 3, and by reason of its engagement with the arm 26 forces the latter up, and the arm 27 also rises and lifts the stop 21; said arm 27 loosely pivoted at 30 to said stop 21, said stop rising immediately in front of the column stop on which the active tappet 17 is formed, as at Fig. 3, and serving to arrest the carriage. Said finger or device 24 is pivoted at its lower end to the top of a vertically sliding member 31 formed at its lower end with a cross-arm 32, the lower edge of the latter formed with steps 33, one for each of the keys 10. Beneath these steps is a row of projections 34 extending upwardly from the rear ends of a set of levers 35 fulcrumed upon a transverse horizontal rod 36 and at their forward ends pivotally connected at 37 to vertical stems 38 bearing the keys 10. It will now be seen

that when any key 10 is depressed, as for instance the key bearing the number "7", Fig. 3, the lever 35 is turned and the projection 34 on the rear end thereof is raised to engage the seventh step 33, thus lifting the vertically sliding member 31 and the pivoted device 24 thereon to such a position that the top of said pivoted device 24 will be in the path of that tappet 17 which is formed on the column stop that bears the number 7, Fig. 3, but not high enough to occupy a position in the path of any of the first six tappets. Hence when the carriage is released, it will run along under the influence of the spring barrel 7 until the seventh tappet 17 strikes the pivoted device 24 and swings the same to cause the lever 26, 27 to lift the stop 21 into the path of the seventh column stop 11, thus arresting the carriage.

The stroke of the keys 10 and lever 35 is uniform, and the provision of the stops 33 enables the member 31 and the interponent 24 to be thrust up far enough to be engaged by any tappet, without engaging the preceding tappets. The first tappet in the row is the highest and accordingly the first step on the member 31 is the lowest, thus enabling the first lever 35 to impart the longest stroke to 31 and 24, to enable the latter to reach a position in the path of the first or highest tappet 17. The next tappet is a little lower, and the second lever 35 is adapted to engage the second step 33, so as to thrust up 24 high enough to meet the second tappet 17 while escaping the first tappet; and so on throughout the series. Each of said projections 34 is also adapted to engage a horizontal universal bar 38, the same constituting the lower edge of a vertical plate 39 engaging guide screws 40 by means of vertical slots 41. A projection 42 on the front of said plate 39 engages a lever or arm 43 fixed to a rock shaft 44 upon the framework; another arm 45 on said rock shaft being pivoted at 46 to the lower end of a link 47; the upper end whereof is pivoted at 48 to a lever 49 pivoted at 50 upon the framework and carrying at its forward end the usual roll 51 to lift the rack 8 on its hinge 53 out of engagement with the pinion 9 to release the carriage for tabulating. Upon release of pressure from the key 7, the parts are returned to normal positions by springs 54 and 55; springs 56 serving to return the key levers and keys. Upon the rock-shaft 44 is secured the usual barrel 57 containing a rotary brake operated by a pinion 58 mounted on said barrel to be rocked about the axis 44 into mesh with a gear 59 provided on the spring barrel 7.

For convenience in securing the key stems 38 each of them is provided with a keeper 60 swiveled at 61 to the body of the key stem and having at its lower end a perforation 62 to fit upon a nipple 63 provided upon the end of the stud 37, which forms the pivotal con-

nection between the key stem and the lever 35, Fig. 4; the lever being perforated to receive said stud. The stem 38 and keeper 60 are made of sheet metal, and the stem is off-
set at 64 below the pivot 61 of the keeper, the latter being flat, so that room is made between the stem and the keeper to receive the lever 35. As these stems 38 usually have to pass down between closely arranged type-
key levers 65, Fig. 2, this method of attaching them is found inexpensive and convenient, and permits ready detachment when required. The key stems 38 are guided in a comb 66 secured upon the framework, and at
their upper ends having shoulders 67 to serve as stops for arresting the keys, the latter having uniform depressions. The key stems are releasably retained in the comb by a keeper bar 68 detachably connected by
screws 69 to the comb 66.

Variations may be resorted to within the scope of the invention, and portions of the improvements may be used without others.

Having thus described my invention, I

claim:

1. The combination with a carriage and a stop, of a series of column stops on the carriage, a set of keys, and means movable by said keys to coöperate with the carriage to project the first stop into the path of any selected column stop for arresting the carriage.

2. The combination with a carriage and a stop, of a series of stops on the carriage to co-operate with said stop, and means to enable the carriage by its movement in letter-feeding direction to project the first stop in a direction transverse to the carriage movement, into the path of any selected one of said series for arresting the carriage.

3. The combination with a carriage, a stop, and a set of column stops on the carriage, of a selecting mechanism to coöperate with said carriage to enable the movement of the carriage in letter-feeding direction to cause the first stop to move into the path of any selected column stop.

4. The combination with a carriage, of a series of similar stops on said carriage, a stop upon the framework, and key-controlled means to enable the carriage to cause the framework stop to project into the path of any selected carriage stop.

5. The combination with a carriage and a stop, of a coöoperating stop, a tappet on the carriage, and an interponent movable by a key into the path of said tappet to be operated thereby, said interponent having means to project one of said stops into the path of the other.

6. The combination with a carriage and a stop, of a series of coöoperating stops, a series of tappets associated with said coöoperating stops, an interponent, and means to set said interponent into the path of any selected tappet to be operated thereby, said inter-

ponent having means to project the first stop into the path of that coöperating stop which is associated with the selected tappet.

7. The combination with a carriage and a stop, of a series of coöoperating stops, a series of tappets arranged in echelon and associated with said coöperating stops, an interponent, and variably movable means to set said interponent into the path of any selected tappet to be operated thereby, said interponent having means to project the first stop into the path of that coöperating stop which is associated with the selected tappet.

8. The combination with a carriage, of a set of column stops, a set of tappets associated with said column stops, a set of column keys, an interponent, means controlled by the keys to effect variable relative movement between the tappets and the interponent, to enable the latter to be operated by any selected tappet, and a stop projected by said interponent into the path of the column stop which corresponds with the selected tappet.

9. The combination with a carriage, of a set of column stops, a set of tappets associated with said column stops, a set of column keys, an interponent, means controlled by the keys to effect variable relative movement between the tappets and the interponent, to enable the latter to be operated by any selected tappet, and a stop projected by said interponent into the path of the column stop which corresponds with the selected tappet, each of said tappets connected to its column stop to be adjustable therewith to different positions upon a rack.

10. The combination with a carriage, of a set of column stops, a set of tappets arranged in echelon, a set of column keys, an interponent movable by said keys variable distances into the paths of the tappets to be operated by the latter, and a stop projected by said interponent into the path of said column stops for arresting the carriage.

11. The combination with a carriage, of a set of column stops, a set of tappets arranged in echelon, a set of column keys, an interponent movable by said keys variable distances into the paths of the tappets to be operated by the latter, and a stop projected by said interponent into the path of said column stops for arresting the carriage, each of said tappets formed in one piece with its associated column stop, and adjustable therewith along a rack.

12. The combination with a carriage, of a set of column stops, a set of tappets arranged in echelon, a set of column keys, an interponent movable by said keys variable distances into the paths of the tappets to be operated by the latter, and a stop projected by said interponent into the path of said column stops for arresting the carriage, each of said tappets formed in one piece with its

associated column stop, and adjustable therewith along a rack, the column stop consisting of a forked member, and the tappet being formed on one of the forks.

5 13. The combination with a carriage, of a set of column stops, a set of tappets connected to said column stops and disposed in echelon, a set of column-stop keys, an interponent movable variably by said keys into 10 the path of the tappets, to be operated by any selected tappet, and a stop upon the framework projected by said interponent into the path of the corresponding column stop to coöperate therewith to arrest the 15 carriage.

14. The combination with a carriage, of a stop thereon, a tappet also on the carriage, a key upon the framework, an interponent movable by said key into the path of the 20 tappet to be operated by the latter, and a stop upon the framework projected by said interponent into the path of said carriage stop to coöperate therewith to arrest the carriage.

25 15. The combination with a carriage, of a series of column stops, each provided with a tappet, the tappets being disposed in echelon, a set of keys, a setting device variably movable by said keys, a part movable by 30 said setting device toward the row of tappets to be operated by different tappets according to the extent of movement of said setting device, and a stop projected by said movable part into the path of the selected column 35 stop to arrest the carriage.

16. The combination with a carriage, of a series of stops, each provided with a tappet, the tappets being disposed in echelon, a set of keys, a stepped setting device, members 40 operated by said keys to engage said stepped setting device to move the latter variably, an interponent adjustable to different positions by said setting device to be operated by different tappets according to the position to 45 which said interponent is projected, and a stop caused by said interponent to project into the path of the selected stop in said series.

17. The combination of a series of keys, 50 a series of members operated thereby, a stepped device engageable by said key-operated members to be adjusted different distances by the latter, a device pivoted upon said stepped member, a series of tappets arranged in echelon upon a carriage and connected to a series of stops, said pivoted device movable by said stepped member variable distances into the path of any selected tappet to be turned thereby at the movement of the carriage, and a stop caused by 60 said pivoted device to move into the path of the stop in said series which corresponds with the active tappet.

18. The combination of a series of keys, 65 a series of members operated thereby, a

stepped device engageable by said key-operated members to be adjusted different distances by the latter, a device pivoted upon said stepped member, a series of tappets arranged in echelon upon a carriage and connected to a series of stops, said pivoted device movable by said stepped member variable distances into the path of any selected tappet to be turned thereby at the movement of the carriage, and a lever caused by 75 said pivoted device to move a stop into the path of the stop in said series which corresponds with the active tappet.

19. The combination of a series of keys, 80 a series of members operated thereby, a stepped device engageable by said key-operated members to be adjusted different distances by the latter, a device pivoted upon said stepped member, a series of tappets arranged in echelon upon a carriage and connected to a series of stops, said pivoted device movable by said stepped member variable distances into the path of any selected tappet to be turned thereby at the movement of the carriage, a stop caused by 85 said pivoted device to move into the path of the stop in said series which corresponds with the active tappet, and a spring to turn said pivoted device back to normal position.

20. The combination of a series of keys, 90 a series of members operated thereby, a stepped device engageable by said key-operated members to be adjusted different distances by the latter, a device pivoted upon said stepped member, a series of tappets arranged in echelon upon a carriage and connected to a series of stops, said pivoted device movable by said stepped member variable distances into the path of any selected tappet to be turned thereby at the movement of the carriage, a stop caused by 95 said pivoted device to move into the path of the stop in said series which corresponds with the active tappet, and a spring to turn said pivoted device back to normal position. 100

21. The combination with a carriage having a column-stop rack, of a series of numbered column stops to engage said rack, each 115 column stop having a tappet, and the tappets being disposed in echelon, a set of column stop keys, levers operated by said keys, a stepped setting device engageable by said levers, to be movable different distances by 120 different levers, a part pivoted upon said stepped setting device to be moved thereby variable distances toward the series of tappets to be engaged by different tappets, according to the extent of projection of the pivoted part by the operated key, a lever operable by said pivoted part when the latter is vibrated by the tappet, and a stop projected by said lever into the path of the selected column stop to coöperate therewith to 125 130

arrest the carriage at the column corresponding to the operated key.

22. The combination with a carriage having a column-stop rack, of a series of numbered column stops to engage said rack, each column stop having a tappet, and the tappets being disposed in echelon, a set of column stop keys, levers operated by said keys, a stepped setting device engageable by said 10 levers, to be movable different distances by different levers, a part pivoted upon said stepped setting device to be moved thereby variable distances toward the series of tappets to be engaged by different tappets, according 15 to the extent of projection of the pivoted part by the operated key, a lever operable by said pivoted part when the latter is vibrated by the tappet, a stop projected by said lever into the path of the selected column stop to 20 coöperate therewith to arrest the carriage at the column corresponding to the operated key, a universal bar operated by said keys, and carriage-releasing means connected to said universal bar.

25. 23. The combination with a carriage and a stop, of a series of column stops, a set of keys, means movable by said keys to coöperate with the carriage to project the first stop into the path of any selected column 30 stop for arresting the carriage, and carriage-releasing means operated by said keys.

24. The combination with a power-driven carriage, a letter-feeding mechanism, and a carriage-stop, of a series of stops to coöperate 35 with the first stop, a stop-selecting device having means to enable the carriage, by its movement in letter-feeding direction, to effect a relative projecting movement between the first stop and any selected stop in 40 said series, for arresting the carriage, and carriage-releasing means operated by said stop-selecting device.

25. The combination with a power-driven carriage, a letter-feeding mechanism and a carriage-stop, of a coöperating stop, a tappet, an interponent movable by a key into 45 the path of said tappet to be operated thereby, said interponent having means to pro-

ject one of said stops into the path of the other, and a carriage-releasing device also 50 operable by said key.

26. The combination with a power-driven carriage, a carriage-feeding mechanism, and a carriage-stop, of a series of coöperating stops, a series of tappets associated with said 55 coöperating stops, an interponent, and means to set said interponent into the path of any selected tappet to be operated thereby and simultaneously release the carriage, said interponent having means to project 60 the first stop into the path of that coöperating stop which is associated with the selected tappet.

27. The combination with a power-driven carriage, a letter-feeding mechanism, and a 65 stop, of a series of coöperating stops, a series of tappets arranged in echelon and associated with said coöperating stops, an interponent, a set of keys, variably movable means operated by said keys to set said interponent 70 into the path of any selected tappet to be operated thereby, and a carriage releasing mechanism also operable by said keys, said interponent having means to project the first stop into the path of that coöperating 75 stop which is associated with the selected tappet.

28. The combination with a power-driven carriage and an escapement mechanism of a series of stops, each provided with a tappet, 80 the tappets being disposed in echelon, a set of keys, a stepped setting device, members operated by said keys to engage said stepped setting device to move the latter variably, a carriage-releasing universal bar also operable by said members, an interponent adjustable to different positions by said setting device to be operated by different tappets according to the position to which said interponent is projected, and a stop caused by 85 90 said interponent to project into the path of the selected stop in said series.
